UNITED STATES PATENT OFFICE.

JAMES M. BARR, OF CHICAGO, ILLINOIS.

EXCAVATOR.

SPECIFICATION forming part of Letters Patent No. 550,152, dated November 19, 1895.

Application filed April 30, 1894. Serial No. 509,496. (No model.)

To all whom it may concern:

Be it known that I, JAMES M. BARR, of Chicago, Illinois, have invented certain new and useful Improvements in Excavators, of which 5 the following is a specification.

The object of my invention is to provide a simple, economical, and efficient portable excavator, especially adapted for use in railway-cutting, &c.; and the invention consists in the 10 features and combinations hereinafter described and claimed.

In the drawings, Figure 1 is a vertical elevation, partly in section; Fig. 2, a detail of the driving-gear; Fig. 3, a plan view of the 15 machine, partly in section, looking at it from the top; Fig. 4, a vertical section taken on line 4 of Fig. 1, and Fig. 5 a front elevation of a portion of the machine.

In the art to which this invention relates, 20 and especially when used for the purpose of making cuts for railroad-beds, it is desirable that an excavator be made that will make a cut the full width of the machine, so that the supporting-truck may follow in such cut. Making 25 the excavation the full width of the machine enables the machine to travel in the cut so made and avoids the necessity (which exists in machines where the travel of supporting-wheels is outside of the width of the cut) 30 of preparing proper wheel-tracks to enable the cut to be made upon a true alignment. This advantage will be readily appreciated when it is understood that ordinarily at points where it is desirable to excavate the ground 35 is very uneven, so that an excavator which does not form its own bed must be provided with proper wheel-tracks, necessitating a certain amount of preliminary grading before such tracks can be laid to perform the excavation, and, further, requires additional labor 40 to perform the final alignment or grading.

The principal object of my invention is to remove many of the objections existing in present structures and provide a portable excavator that will make a cut the full width of the machine, so that the supporting and propelling truck may follow in such cut to make a cut of the proper grade and alignment.

A further object of my invention is to provide an organized portable excavator that is constantly propelled forward in the bed of its own cut, while the excavator operates contin-

uously in cutting and delivering material to a point of deposit.

In constructing my improved portable excavator I use a truck-frame A of the desired form and size, mounted, supported, and pivoted, as hereinafter described, upon two sets of wheels a a'. I preferably provide three helical shovels B, which are rotatably mounted 55 in brackets b b' to the forward end of the truck-frame, such brackets being secured thereto in any convenient manner, preferably by means of bolts and nuts. To rotate these helical shovels, I prefer to use an engine C, mounted or supported on the truck in any convenient manner so as to rotate a main shaft c with its two sprocket-wheels D, the rotation of the main shaft being imparted to the helical shovels through the sprocket-wheels D, the chain d', and sprocket-wheel d'. The helical shovels are so arranged as to 60 make a cut slightly wider than the truck following, so that the truck may follow directly in the bed of the cut, thus dispensing with the necessity of laying tracks. These shovels are 65 partially surrounded by a casing E of the proper form and size, so that the material which is taken up by these shovels is kept in contact with their helical grooves and forced 70 back upon proper conveyers, to be removed to any desired point. To convey the waste material from the shovels to a proper receptacle or desired point, I provide an initial belt-conveyer G, which is mounted on pulleys g, having shafts and bearings in the side frame of the machine, and which are rotated by means of sprockets g' g² and sprocket-chain g³, particularly shown in Fig. 2. To 75 convey the waste material from this initial 80 conveyer, I provide a secondary belt-conveyer H, mounted upon rotating cylinders or pulleys h and driven by means of sprocket-chains h³ on one of the pulley-shafts. This 85 sprocket-chain may be connected by means of suitable power-transmitting mechanism 90 with the engine-shaft, but which I deem it unnecessary to show or describe here in detail. The material is conveyed back by the secondary conveyer to either a dump-car, 95 which may convey it to a spoil-bank or other suitable place of deposit, or another conveyer 100 of any description may be provided by which the spoil or waste material is conveyed to the

spoil-bank; but this feature I do not claim and forms no part of my invention.

It is often desirable and necessary to raise and lower the rotating helical shovels, so as to excavate at any depth that may seem economical, either to the full diameter of the helical shovels or but a very small portion of their diameter. It is also desirable to so raise and lower the helical shovels that an excavation may be formed at any desired grade or incline in which the truck may follow. To accomplish this result I pivot the truck-frame upon the axle I of the rear truck-wheels, and in such manner as that the entire front of the truck and all the operative machinery thereon may be raised. I prefer to divide the truck-frame into two sections i i' and provide the section i with a segmental rack i^2 , which is rigidly secured to it and the second section by means of bolts or in any convenient manner. I provide the forward truck-wheels with a pivotal frame K , which has the ordinary fifth-wheel and king-bolt k , upon which wheels turn so as to turn the truck around any desired corner or curvature. Secured in suitable bearings at the upper portion of this pivotal frame is a shaft k' , provided with pinions k^2 , one at each end, which engage with the segmental rack of the truck-frame in such manner that the rotation of the shaft k' and its pinion k^2 will raise and lower the segmental rack, and with it the front end of the truck-frame, which action raises and lowers the helical shovels to engage with the material to be excavated at the desired depth. This shaft is provided with the sprocket-wheel k^3 , which may, by means of a sprocket-chain, be connected to the main engine-shaft in such manner that the power of the engine may be used to lower or raise the truck-frame.

It is often desirable to propel the entire truck by mechanical power as the helical shovels are working, so that they will make the proper advancement or feed into the cut and remove the earth as fast as seems necessary in a regular and constant manner. To accomplish this result I provide the rear truck-wheels with an internal annular gear L , and mounted on the truck-frame in suitable bearings is a shaft l , having a pinion l' at each end, meshing and engaging with the annular gear of the truck-wheels. This shaft may be provided with a sprocket-wheel or a set of bevel-gears and be engaged by means of suitable gearing with the main driving-shaft of the engine, so that during the rotation of this driving-shaft motion will be imparted to the rear truck-wheels and propel the truck forward at any desired rate of speed, it being understood, of course, that the gearing is so proportioned that the proper forward motion of the truck may be attained.

The truck-wheels may be of the ordinary flat type and provided with corrugated metal tires, by which the excavator may be moved along the bed or cut, or they may be provided with flanged tires and of the gage used

in railroad construction and the cut provided with a suitable track upon which the truck, with its wheels, may be moved along as desired.

In operation, the machine is moved into position to make the desired excavation and the mechanism rotated. The forward movement of the machine carries the helical shovels into engagement with the face of the cut. As the machine advances and the shovels rotate, the material is carried back upon the initial conveyer, thence to the second conveyer, and thence by means of this conveyer to a suitable dump-car, which may follow in the wake of the excavating-machine, and which, when loaded, will be removed and an empty one supplied in its place. The machine may be moved along a straight line, taking out the desired amount of material the first time until the entire length of the cut has been traversed, when the apparatus may be either moved back to its initial starting-point and the excavation started at a new depth, or the cut widened, as desired, the movements of the whole apparatus being under control of one operator.

The principal advantages of my improved excavator are that I have provided an excavator in which is arranged and combined helical shovels, a pivotal supporting-truck, and mechanism for propelling the truck forward in the bed of the cut, so that a cut for railroad and similar purposes may be made without the necessity of laying a track. Further, the excavator can be adjusted in such a manner that a continuous cut can be made at any desired grade or incline; and, finally, I have provided a machine that excavates or removes material from a point of excavation, delivering it to a point of discharge, all operating in a continuous manner.

I claim—

1. A portable excavator, comprising a supporting and propelling truck, wheels upon which such truck is moved and mounted, a plurality of rotating cutting shovels mounted in a horizontal plane at the forward end of the truck, means for operating the shovels and propelling the truck forward continuously, and an inclosing case provided with a horizontal portion arranged to deflect and guide the material toward the cutting shovels and in combination therewith to excavate a substantially level cut the full width of the machine, substantially as described.

2. A portable excavator, comprising a supporting and propelling truck, wheels upon which such truck is moved and mounted, at least three helical shovels rotatably mounted in a horizontal plane at the forward end of the truck, an inclosing case provided with a horizontal cutting edge to deflect and guide the material toward the helical shovels and in combination therewith to excavate a substantially level cut the full width of the machine, belt conveying mechanism located on the truck to receive the material excavated

by the shovels and to deliver it to a point of discharge, and a motor arranged on the truck for propelling the same forward and operating shovels and conveyers in a continuous manner, substantially as described.

3. A portable excavator comprising a truck provided with wheels pivotally mounted upon one pair of the supporting wheels and adapted to support and move the operating mechanism, a rack and pinion for raising and lowering the truck with its operative mechanism upon the pivotal axle, one or more rotatable, helical shovels mounted on such truck in a horizontal, longitudinal position, a casing secured to the truck and partially surrounding the shovels for deflecting and guiding the material to be excavated into contact with the rotatable shovels, belt conveyers secured to the truck for taking and delivering the waste material to a point of deposit, and a motor upon such truck for operating the rotatable excavators and conveyers, substantially as described.

4. A portable excavator comprising a supporting truck provided with wheels upon which the operative mechanism is supported

and mounted and pivoted to the rear pair of wheels so that the front end of the truck may be raised or lowered, rack and pinion mechanism secured to the frame and front pair of wheels for raising and lowering the free end of the truck, one or more rotatable, helical shovels mounted at the free vibrating end of the truck in a horizontal, longitudinal plane, a casing secured to the truck and partially inclosing the shovels for deflecting and guiding the earth to be excavated and keeping it in contact with the shovels during the rotation, belt conveying mechanism on the truck for receiving and conveying the waste material to a point of deposit, gear mechanism secured to one of the wheels and the frame of the truck to move the excavator forward or backward as desired, and a motor mounted on such truck and arranged to rotate the excavators, belt conveying mechanism and to move the truck forward or backward, substantially as described.
